UNITED STATES PATENT OFFICE.

HARRY C. CABLE, OF LOS ANGELES, CALIFORNIA, ASSIGNEE TO MORGAN L. SWEENEY AND EDWARD J. BOWEN, BOTH OF LOS ANGELES, CALIFORNIA.

OIL-WELL CASING.

Application filed September 18, 1921. Serial No. 300,001.

To all whom it may concern:

Be it known that I, HARRY C. CABLE, a citizen of the United States, residing at Los Angeles, in the county of Los Angeles and State of California, have invented a new and useful Oil-Well Casing, of which the following is a specification.

My invention relates to oil well casing and particularly to such casing known as riveted casing.

One of the most objectionable features of riveted casing as at present manufactured is that it pulls apart at the joints by shearing the rivets. This has partly been overcome by picking, an operation resorted to for the purpose of making a better frictional contact to reduce the slip between the outer and inner pipes of which the casing is made. The picking method does not produce the desired result owing to the fact that the pick marks do not cover enough surface and disengage when subjected to the strain of pulling or driving a casing in the well.

My invention has for its object the production of a sectional casing that may be handled at the well, the same as the standard steel casing, and one that will stand up under the same use and greater abuse to which such casing is subjected.

Another object of my invention is to produce a casing in which the rivets at the joints will not shear when the casing is being driven or pulled in a well.

Another object of my invention is to produce a sectional casing that will not buckle under severe compression strains.

Another object of my invention is to produce a casing which can be easily handled by an elevator commonly used in the oil field, for raising or lowering casing in the well.

Further objects and advantages will appear hereinafter in the description.

Referring to the drawings which are for illustrative purposes only,

Fig. 1 is a side elevation of my improved oil well casing.

Fig. 2 is a vertical section of the same.

Fig. 3 is a section on line 3—3 of Fig. 1.

Fig. 4 is a view showing how the casing is held by an elevator.

Like numerals of reference refer to like parts in the several figures.

My invention consists of an oil well casing

10 formed of inner and outer riveted sheet 85 metal pipes 11 and 12, each consisting of a series of pipe sections 13 having their ends 14 abutting, forming joints 15 and 16, the joints 15 in the inner pipe 11 being staggered with relation to the joints 16 in the outer 60 section so that no two joints lie in the same plane.

The pipes 11 and 12 are held together by rivets 17 at the joints 15 and 16, these rivets being driven through both the outer 65 and inner pipes securely fastening the sections together.

Casing made as above described stands up well under ordinary conditions, but when such casing is subjected to several pulling 70 or compression strains, such as arise when pulling casing from the well, or driving same in the well, the rivets shear at the joints due to slip between the outer and inner pipes, this slip allows relative movement between the outer and inner pipes to shear the rivets and pull the joints apart or telescope the casing.

To insure against slip of this nature and to stiffen the casing against lateral strains, so I form annular beads or ribs 18 between the joints 15 and 16 where the pipe sections are abutted, the ribs 18 forming locks between the outer and inner pipes which cannot be pulled apart without rupture of the pipe. 80 The ribs 18 are formed in one operation and consist in fact of a rib 19 formed on the inner pipe which engages into an annular groove 20 formed in the outer pipe by forming an annular bead or rib 21 therein. 85

The ribs 18 also form shoulders which are engaged by the top of the elevator 22 as shown in Fig. 4, such elevator being commonly used in oil well rigs for raising and lowering casing in the well, and greatly 90 facilitates the handling of such casing.

The casing is assembled by placing an outer section of pipe 12 over an inner section 11, allowing approximately one-half of the inner section of pipe to extend beyond the end of the outer section and driving a row of rivets 17 to hold both sections in place while the bead or rib 18 is being formed. Another outer section of pipe 12 is placed over the extended portion of the inner section 11, the ends of both outer sections of pipe 12 abutting and a row of rivets 17 driven to hold this section in place while

a second bead or rib 18 is formed on the opposite side of the abutting ends of the pipe 12 to that previously beaded.

We now have a length of casing composed of two outer and one inner sections of pipe, with the outer sections extending beyond the inner section one-half its length, into which is placed an inner section, the ends of the inner sections abutting. The sections are then riveted and beaded on both sides of the abutted edges. A casing of any desired length may be fabricated by alternately assembling the sections as described.

While I have shown and described the sections as being fabricated by riveting the outer and inner pipes together, it is to be understood that such riveting is not entirely essential as the outer and inner pipes may be secured to each other solely by the beading heretofore described.

I claim as my invention:

1. An oil well casing comprising: a series of inner sections of substantially the same diameter placed with their ends abutting; a series of outer sections of the same diameter but of a slightly larger diameter than said inner sections placed with their ends abutting the joints between the inner sections being staggered with relation to the joints between the outer sections; two rows of rivets for each joint each of said rivets passing through one

of said inner sections and one of said outer sections and being counter-sunk on the inner side of said casing; and a series of annular ribs each formed by increasing the diameter of the material of said inner and outer sections which are thereby locked together, the casing being of substantially uniform diameter for a sufficient distance between said ribs, to allow space for the attachment of an elevator.

2. An oil well casing comprising: a series of inner sections of substantially the same diameter placed with their ends abutting; a series of outer sections of the same diameter but of slightly larger diameter than said inner sections placed with their ends abutting, the joints between the inner sections being staggered with relation to the joints between the outer sections; and a series of annular ribs each formed by increasing the diameter of the material of said inner and outer sections which are thereby locked together, the casing being of substantially uniform diameter for a sufficient distance between said ribs, to allow space for the attachment of an elevator.

In testimony whereof, I have hereunto set my hand at Los Angeles, California, this 31st day of August, 1921.

HARRY C. CABLE.
